FIG 12.

UNITED STATES PATENT OFFICE.

WILLIAM T. BARRATT, OF BENNINGTON, VERMONT.

STRIPING ATTACHMENT FOR CIRCULAR-KNITTING MACHINES.

SPECIFICATION forming part of Letters Patent No. 778,164, dated December 20, 1904.

Application filed August 25, 1903, Serial No. 170,700.

To all whom it may concern:

Be it known that I, WILLIAM T. BARRATT, a citizen of the United States, residing at Bennington, in the county of Bennington and State of Vermont, have invented new and useful Improvements in Striping Attachments for Circular-Knitting Machines, of which the following is a specification.

My invention relates to improvements in striping attachments for circular-knitting machines; and the object of my invention is to simplify and cheapen the construction of devices of this character and at the same time to make their operation more certain and accurate.

In the accompanying drawings, Figure 1 is a side elevation of my improved attachment with the yarn-dropper, yarn-cutter, and holder removed, the attachment being shown in connection with a portion of the needle-cylinder, which is shown in section. Fig. 2 is a similar view, but in which the yarn-fingers are omitted and the yarn dropper, holder, and cutter illustrated. Fig. 3 is an edge view looking in the direction indicated by the arrow, Fig. 2. Fig. 4 is a view in side elevation, showing the stitch-wheel, the yarn-guide, and the yarn holder, cutter, and dropper, all being shown in connection with a portion of the needle-cylinder, the latter being shown in vertical section. Fig. 5 is a detached enlarged perspective view of the combined yarn cutter and holder and the yarn-dropper. Fig. 6 is an enlarged detached view of the yarn-guide. Fig. 7 is a diagrammatic view of the cams carried by the needle-cylinder which coöperate with certain parts of the mechanism to be hereinafter described. Fig. 8 is a relatively enlarged side elevation of a portion of the needle-cylinder, showing the cams which are carried thereby and coöperate with parts of the mechanism. Fig. 9 is a detached perspective view of the movable member A of the yarn holder and cutter. Fig. 10 is a detached perspective view of the stationary member of the yarn-cutter. Fig. 11 is a detached perspective view of the stationary member of the yarn-holder. Fig. 12 is a top plan view of my improved attachment, showing it ar-

ranged in connection with a portion of the 50 needle-cylinder.

Referring now to the drawings, A indicates the needle-cylinder, which carries the needles B, the operation of both of which being so well understood in the art that further description or illustration thereof is unnecessary.

D is a bracket or stand which is suitably supported adjacent the needle-cylinder A, and this bracket carries a pattern-wheel 17. The operation of the several parts of the mechanism is controlled by the movement of the pattern-wheel, which, broadly considered, is old in the art. A cam carried by the needle-cylinder (to be fully described hereinafter) causes the pattern-wheel to move one tooth for each 65 revolution of the needle-cylinder.

The several colored yarns are carried by yarn-fingers, and these yarn-fingers are moved to throw the respective yarns into and out of the stitch-wheel. There show two yarn-fingers 70 10 and 10, which are carried, respectively, by bell-crank levers G, and these levers G are intermediately pivoted to the upper ends of cam-levers G', each of which carries a cam 13. The levers are pivoted at the point J upon a 75 suitable bracket or arm K, and the lower ends L of these levers are guided by a suitable slotted plate 18. The inner ends of the bell-crank levers G are slotted, as shown at g, and into these slots project a pin h, carried by a suitable arm or bracket z.

The periphery of the pattern-wheel 17 is provided with a plurality of openings which are adapted to receive suitable screws or pins 80 12, and these openings are arranged in circular series, as clearly shown in Fig. 3. The cams 13, carried by the cam-levers G', are adapted to coact with the pins or screws of these openings, the cam carried by one lever coacting with one of the circular series of screws and the cam or cams of the other lever or levers coacting with other circular series of the said screws. When the cam of one of these levers G' is engaged by the screw of its series, it is moved into the position to move 85 the yarn-finger upward into the position shown by the yarn-finger 10, Fig. 1, and thus carrying the yarn out of operation.

Springs 19 and 20 are respectively connected with these levers G' and serve to normally draw them inward and to normally hold the yarn-fingers in the position assumed by the 5 finger 10 in Fig. 1, and hence to hold the yarn in the position to enter into the stitch-wheel. From this it will be readily understood that the placing of the screws in the openings of the series formed in the pattern-wheel will 10 control the positions of the yarn-fingers, and hence control the throwing of the yarn into and out of the stitch-wheel. For instance, the omission of one or more of the screws from the series of openings coacting with the 15 cam-lever carrying the yarn-finger will cause the yarn-finger to be dropped or moved into position to cause the yarn to be carried into the stitch-wheel, and the placing of the screws in the openings will cause the yarn-finger to 20 be lifted and the yarn carried out of the stitch-wheel.

In machines of this character it is necessary to cut and to hold the yarn which is carried out of the stitch-wheel until it is desired to have the 25 yarn to again enter the stitch-wheel. My improved mechanism for accomplishing this consists of a vertically-arranged stationary cutter C and a movable cutter A'. The movable cutter is journaled upon a suitable pivotal arm M, 30 and secured rigidly to the cutter-blade A' is a rod I, to the outer end of which is attached a spring 31, which normally holds the cutter closed. The cutter is opened into the position shown in Fig. 2 through the medium of 35 the lever 14, a link 15 having one end connected to the lever and its opposite end connected to a crank-arm 26, which is carried by an oscillating rod 3, the outer end of this rod 3 carrying a crank-arm 3', which in turn is 40 provided with a wheel or truck 29, which is adapted to be engaged by a cam a at the under side of the needle-cylinder A. A spring 35 normally holds the said parts in the position shown in dotted lines, Fig. 3, and the 45 cam a serves to carry the parts in the position shown in solid lines, Fig. 3. When moved in the position shown in solid lines, Fig. 3, an arm 27, rigidly connected with the bar 3, is caught and held by a latch-lever 4. When 50 the parts are held in this position, the upper end of the lever 14 engages the under side of the rod I and raises it against the tension of the spring 31, and hence holds the cutter-blade a' in an open position, as shown in Fig. 55 2. The upper end of the latch-lever 4 is provided with a shoulder 6, adapted to be engaged by a long screw 5, projecting from the periphery of the pattern-wheel 17. When so engaged, the latch-lever is moved into the 60 position shown in dotted lines, Fig. 3, and thus releases the arm 27, which permits the spring 35 to oscillate the rod 3 and carry its parts into the position shown in dotted lines, Fig. 3. When the cam a engages the truck

29, the lever 14 is depressed, which permits 65 the spring 31 to draw the rod I downward and to close the cutter-blade a'. When the yarn is cut, it has a tendency to drop, and hence a suitable holder must be provided, and for the purpose of making the cutter-blade 70 coact with a stationary member D' and effect a positive holding of the yarn the adjacent faces of the cutter-blade a' and of the member D' are each provided with felt pads N, which serve to positively grasp the cut end 75 of the yarn and to firmly hold it until it is released by the opening of the cutter-blade.

A stitch-wheel 19 is carried by an arm or bracket P, and this arm or bracket is supported by a suitable standard Q. Also projecting 80 from the standard Q is a yarn-guide 23, and this yarn-guide is provided with a hook 22, into which the yarn is thrown as it is raised above the back of the needles by the raising of the yarn-finger, and the hook holds the yarn 85 so that it continues to be fed to the stitch-wheel until the new yarn which has been dropped by the dropping of the yarn-finger carrying it has reached the stitch-wheel. The rotation of the needle-cylinder toward the end 90 of the guide carries or pushes the yarn off of the hook 22 and elevates the yarn to the top of the needles and also carries it between the movable and stationary cutters at the point marked X, Fig. 2.

The yarn-dropper E is carried or operated by a lever 1, the opposite end of the lever being pivoted to an arm 16. A cam 8 is carried by the lever 1, and this cam is adapted to be engaged by screws 7, placed in a series of 100 openings formed in the side of the pattern-wheel 17. The screws 7 serve to elevate the lever 1, and hence elevate the yarn-dropper E. The omission of the screws permits the lever 1, and hence the yarn-dropper, to be drawn downward or dropped, and a spring S serves to cause the parts to drop. The purpose of the 105 yarn-dropper is to carry the yarn down at the back and between the needles and to make sure that the yarn will be pushed onto the 110 yarn-guide and pass into the stitch-wheel 19.

As clearly shown, the pattern-wheel is provided with peripheral ratchet-teeth T, and a pawl W is adapted to engage these teeth for rotating the pattern-wheel one tooth. The 115 pawl is actuated by a lever 2, which carries a wheel or truck 20, and this truck 20 is adapted to be engaged by the cam-surfaces b, c, and d, Figs. 7 and 8, carried by the needle-cylinder in a manner to be presently explained 120 when stating the operation of the mechanism.

The operation of my improved striping mechanism is as follows: The parts being in the position indicated in Figs. 1 and 2, the yarn carried by the yarn-finger 11 is entered into the stitch-wheel, while the yarn carried by the finger 10 is thrown out of the stitch-wheel. The yarn carried by the finger 11 con-

tinues to enter the stitch-wheel, and the rotation of the needle-cylinder A causes the cam b to engage the truck 20, which moves the pawl W just sufficiently to engage a tooth of the pattern-wheel. The continued rotation of the needle-cylinder brings the cam-surface c into engagement with the truck 20, and thereby moves the lever 2 farther back, and hence moves the pawl W farther, and begins the rotation of the pattern-wheel sufficiently to cause the screws of the pattern-wheel which coact with the yarn-finger 10 to disengage the cam 32 and permit its lever G' to be drawn inward by its spring 20, and hence throws the yarn 15 carried thereby into action and makes the joining of the yarn into the fabric. As the needle-cylinder continues to revolve the truck 20 is brought into engagement with the cam-surface d, which revolves the pattern-wheel 20 still farther and brings the screw-pin 5 in contact with the upper end of the pivoted lever 4 and moves it into the position shown in dotted lines, Fig. 3, against the tension of the spring 18' and releases the arm 27, 25 which causes the cutter-blade a' to be opened by the upward movement of the lever 14 in the manner previously described. This movement of the pattern-wheel at the same time causes the screws coacting with the lever G', 30 with which the yarn-finger 11 is connected, to engage the cam 13 of the said lever G', thus forcing the lever outward and raising the yarn-finger 11 and throwing its yarn out of action, and the yarn is carried in the manner 35 previously described between the cutters. The continued rotation of the needle-cylinder causes the cam a to engage the truck 29, which draws the lever 14 downward, as before explained, and the spring 31, connected to the 40 rod I, closes the cutter-blade a', cutting the yarn and also positively holding it between the padded surfaces N of the cutter-blade and the member D'. This operation is repeated at each revolution of the needle-cylinder A, 45 or it may be repeated several times during the operation of the cylinder A by providing the needle-cylinder with several sets of the cams a and b c and d and correspondingly arranging the screws carried by the pattern-wheel and providing a suitable number of pins 5, this being merely a duplication or

multiplication of the operation of my invention.

Having thus described my invention, what I claim as new, and desire to secure by Letters 55 Patent, is—

1. A striping attachment for knitting-machines, including a rotatable pattern-wheel, a rotatable needle-cylinder, means whereby the cylinder causes the rotation of the pattern-wheel, a movable yarn-finger actuated by the pattern-wheel, a yarn-guide and a stitch-wheel, and a yarn-dropper controlled by the pattern-wheel for causing the yarn to engage the yarn-guide. 60

2. In a striping attachment for knitting-machines, a vertically-arranged yarn cutter and holder, and a vertically-movable yarn dropper and guide adjacent said holder and means for operating said parts. 70

3. In a striping attachment for knitting-machines, movable yarn-fingers, a pattern-wheel and a yarn-dropper controlled by the movement of the pattern-wheel.

4. In a striping attachment for knitting-machines, movable yarn-fingers, a pattern-wheel, a yarn-dropper, including a lever pivoted at one end, and a vertical member pivoted to the free portion of said lever, the lever being operated by the movement of said 80 pattern-wheel. 75

5. In a striping attachment for knitting-machines, movable yarn-fingers, a pattern-wheel, and a normally depressed yarn-dropper, said pattern-wheel adapted to lift said 85 yarn-dropper and to control its downward movement.

6. In a striping attachment for knitting-machines, a pattern-wheel, movable yarn-fingers controlled thereby, a yarn holder and 90 cutter, a yarn-dropper, and operative connections for the holder and dropper adapted to drop the dropper when the holder is released.

In testimony whereof I have hereunto set 95 my hand in the presence of two subscribing witnesses.

WILLIAM T. BARRATT.
